UNITED STATES PATENT OFFICE.

JOSEPH B. MOORE, OF BEAUMONT, TEXAS.

DRY CLOSET.

1,309,742.

Specification of Letters Patent.

Patented July 15, 1919.

Application filed April 12, 1919. Serial No. 289,487.

To all whom it may concern:

Be it known that I, JOSEPH B. MOORE, a citizen of the United States, residing at Beaumont, in the county of Jefferson and State of Texas, have invented certain new and useful Improvements in Dry Closets, of which the following is a specification, reference being had to the accompanying drawings.

10 This invention relates to certain improvements in dry closets, and it is an object of the invention to provide a device of this general character having novel and improved means whereby the excrement or 15 fecal matter and urine will be effectively separated.

It is also an object of the invention to provide a device of this general character including a yieldably supported member 20 adapted to contact with the buttocks at a point in advance of the anus to effect the requisite separation.

Another object of the invention is to provide a novel and improved device of this 25 general character including a yieldably supported member for the separation of urine from the other matter, together with means coacting with said member to hold the same in a position to facilitate its use in conjunction 30 with a male.

The invention consists in the details of construction and in the combination and arrangement of the several parts of my improved dry closet whereby certain important 35 advantages are attained and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a view in perspective illustrating a dry closet constructed in accordance with an embodiment of my invention with the door included therein shown in a partly open position.

50 Fig. 2 is a view in perspective of the re-

ceptacle or bucket adapted to receive the excrement or fecal matter.

Fig. 3 is an enlarged vertical sectional view taken through the device as illustrated in Fig. 1.

55 Fig. 4 is a fragmentary vertical sectional view showing the separating member for the urine in a second position, and

Fig. 5 is a view in top plan of the means for yieldingly supporting the urine separator and constantly urging the same in one direction.

60 As disclosed in the accompanying drawings, C denotes a chest of predetermined configuration and dimensions and which is provided at a side with a door D so that desired access may be had within the chest. The top T of the chest constitutes a seat and is provided with the conventional opening 1. The rear portion of the top T is 65 provided with a vent opening 2 from which leads a flue 3 for carrying off the vitiated air.

70 Hingedly connected to the top T rearwardly of the opening 1 is a lid or cover L adapted, when lowered, to close the opening 1. The lid L, when raised and partially moved beyond the vertical, contacts with the upstanding blocks or abutments 4 carried by the top T at opposite sides of the flue 3 75 so that the lid or cover L may be employed as a lazy-back and is prevented from striking the flue 3.

80 Insertible within the chest C is the receptacle or bucket R which is adapted to be positioned in the rear portion of the chest C and to underlie the rear portion of the opening 1 in a manner to receive the excrement or fecal matter. The receptacle or bucket R also underlies the vent opening 2 85 so that escape of the vitiated air is assured through the flue 3. The forward portion of the receptacle or bucket R has its wall provided with an inwardly disposed depression 5 for a purpose which will be herein- 90 after more particularly referred to.

95 M denotes a separating member for urine, and said member is substantially funnel-shaped with its forward edge a substantially straight and hingedly connected as at 6 with 100

the forward part of the top T. The upper or flared end portion 7 is rearwardly disposed and of a size to terminate at a point between the anus and the exterior orifice of 5 the vagina or the penis in accordance with the sex of the occupant of the closet so that the requisite separation of the urine is assured.

10 The lower end portion or spout 8 of the member M discharges within the enlarged upper portion 9 of the carry-off pipe P suitably secured to the forward or front wall of the chest C.

15 In the present embodiment of my invention, the lower portion or spout 8 of the member M is loosely disposed through an annular member or ring 10 and engaged with said member or ring 10 at opposite sides of the lower portion or spout 8 are 20 the lower extremities of the retractile members or springs 11. The opposite extremities of the members or springs 11 are suitably anchored to the under face of the top T or other part of the chest so that the members or springs 11 serve to constantly urge 25 the member M upwardly and yet permit the same to have yielding downward movement.

30 By having the members or springs 11 co-acting with the member M as just described, it is assured that the upper edge of the member M at its rear portion will have direct contact with the buttocks of the occupant of the closet and particularly of a female, and the yielding movement of the 35 member M compensates for any desired adjustment of the member M.

When the occupant of the closet is a male, it is of advantage that the rear portion of 40 the flared upper end of the member M be maintained lowered so that the same will be free of contact with the occupant.

45 In the present embodiment of my invention, the member M is maintained in the desired lowered position through the medium of the arm or slide 12 pivotally engaged with the member M and preferably the lower portion of spout 8 thereof and loosely disposed through an opening 14 in the forward or front wall of the chest C. The 50 upper edge of the arm or slide 9 in close proximity to its pivoted connection 15 with the member M is provided with a notch 16 adapted to bridge the upper edge of the opening 14 and thereby maintain the member M in the desired lowered position. The arm or slide 12 at all times extends exteriorly of the chest C so that the lowering of the member M may be accomplished by a direct pull on the slide or arm 12.

60 The depression 5 in the forward wall of the receptacle or bucket R hereinbefore referred to assures the proper positioning of said receptacle or bucket without interference or hindrance to the desired movements

of the members M as the flared portion 7 65 of the member M extends within said depression 5, as is clearly illustrated in Figs. 3 and 4, and wherein said depression is shown to be of a depth to permit the swinging movements of the member M. 70

F denotes a foot-rest positioned adjacent the lower portion of the chest C at the front thereof and for a purpose which is believed to be self-evident.

75 In practice, it is preferred that a sanitation powder consisting either of salted sifted ashes or salted pulverized clay containing a small per cent of either potash, nitrate of soda, or crude saltpeter be used in connection with my improved device, and which 80 powder is placed within the receptacle or bucket R. Initially, about one gallon of this powder is placed within the receptacle or bucket R and substantially one pint added each day.

85 From the foregoing description, it is thought to be obvious that a dry closet constructed in accordance with my invention is particularly well adapted for use by reason of the convenience and facility with 90 which it may be assembled and operated, and it will also be obvious that my invention is susceptible of some change and modification without departing from the principles and spirit thereof and for this reason 95 I do not wish to be understood as limiting myself to the precise arrangement and formation of the several parts herein shown in carrying out my invention in practice except as hereinafter claimed.

100 I claim:

1. A device of the character described comprising a chest having an opening in its top and a funnel-shaped member supported for swinging movement within the chest and 105 partially underlying the opening, and yielding means for constantly swinging the member toward the top of the chest.

2. A device of the character described comprising a chest having an opening in its top and a funnel-shaped member supported for swinging movement within the chest and partially underlying the opening, yielding means for constantly swinging the member toward the top of the chest, and means for 110 locking the member in a lowered position.

3. A device of the character described comprising a chest having an opening in its top and a funnel-shaped member supported for swinging movement within the chest and 115 partially underlying the opening, yielding means for constantly swinging the member toward the top of the chest, and means engaged with the member and extending exteriorly of the chest for swinging the member 120 downwardly.

4. A device of the character described comprising a chest having an opening in its

top and a funnel-shaped member supported for swinging movement within the chest and partially underlying the opening, yielding means for constantly swinging the member toward the top of the chest, and means engaged with the member and extending exteriorly of the chest for swinging the member downwardly, said last-named means co-

acting with the chest for maintaining the member in its lowered position.

10

In testimony whereof I hereunto affix my signature in the presence of two witnesses.

JOSEPH B. MOORE.

Witnesses:

EARL BARRY,
WALTER BARRY.
